(57) **CLAIM**

The ornamental design for an aerodynamic skirt bending member, as shown and described.

DESCRIPTION

FIG. 1 is a perspective view of an aerodynamic skirt bending member.

FIG. 2 is a bottom plan view of the aerodynamic skirt bending member.

FIG. 3 is a top plan view of the aerodynamic skirt bending member.

FIG. 4 is a back elevation view of the aerodynamic skirt bending member.

FIG. 5 is a front elevation view of the aerodynamic skirt bending member.

FIG. 6 is a right hand side elevation view of the aerodynamic skirt bending member; and,

FIG. 7 is a left hand side view of the aerodynamic skirt bending member.
